(57) **CLAIM**

The ornamental design for a multi pocket folder, as shown and described.

DESCRIPTION

FIG. 1 is a front view of the multi pocket folder.

FIG. 2 is a back view thereof;

FIG. 3 is a top view of the multi pocket folder thereof; and,

FIG. 4 is a bottom view of the multi pocket folder thereof.

The broken lines in the drawings illustrate portions of the multi pocket folder and form no part of the claimed design.
